United States Patent Office.

ROBERT SCORER AND ROBERT HAM, OF TROY, NEW YORK.

Design No. 3,676, dated September 28, 1869.

DESIGN FOR THE PLATES OF A STOVE.

The Schedule referred to in these Letters Patent and making part of the same.

To all whom it may concern:

Be it known that we, ROBERT SCORER and ROBERT HAM, of Troy, in the county of Rensselaer, and State of New York, have invented or produced a new and original Design for Heating-Stove Plates, of which the following is a full and exact description, reference being had to the accompanying drawings, and letters of reference marked thereon, making a part of this specification, in which—

Figure 1 is a perspective view of the door-plate and door thereof, and

Figure 2 is a perspective view of the base-part, all of the same stove.

Our said design is composed of ornamental parts, arranged as follows, to wit:

The top edge of the said door-plate is formed of the two ogee-curves *a* and *a'*, and the central curve *b* between them.

The sides and bottom edges of said plate are straight, and surrounded by a bead, *c*.

The door of the said plate has a straight bottom and side edges, and a semicircular top edge.

On the door, next the edges thereof, is disposed the quarter-round moulding *d*, with the series of cross-beads *e*, and next thereto a flat band, with the chain of pyramidal bosses or projections *f*.

The panel of the door is divided into two semicir-

cular top windows by the ornamental mullion *g*; and above said windows, on the door-panel, is disposed a scroll, *h*, all in configuration and disposition as shown in the annexed fig. 1 of the drawings.

The base-part plate of said stove is circular in form, and has projected from its front side a hearth, *i*, upon which is the ash-pit cover-plate *k*.

The bottom edge of the hearth and base is formed of the quarter-round moulding *l*, and next thereto the quarter-round moulding *m*, with the succession of ornamental figures *o* arranged thereon; then, next, the slanting part *p*, with the succession of points *q* disposed thereon; and upon the ash-pit front cover-plate are the ornamental figures *r*, in configuration and arrangement all as shown in fig. 2 of the annexed drawings.

What we claim as our invention and design, and desire to secure by Letters Patent, is—

The ornamental form and design for heating-stove plates, the same as described, and shown in the annexed drawings.

ROBT. SCORER.
ROBT. HAM.
